UNITED STATES PATENT OFFICE

CHESTER A. BACHMAN, OF LOS ANGELES, CALIFORNIA

DESIGN FOR A LAMP OR SIMILAR ARTICLE

Application filed March 18, 1930. Serial No. 34,956. Term of patent 7 years.

To all whom it may concern:

Be it known that I, CHESTER A. BACHMAN, a citizen of the United States, residing at Los Angeles, in the county of Los Angeles and State of California, have invented a new, original, and ornamental Design for a Lamp or Similar Article, of which the following is a specification, reference being had to the accompanying drawing, forming part thereof.

I claim:

The ornamental design for a lamp or similar article as shown.

CHESTER A. BACHMAN.
